UNITED STATES PATENT OFFICE.

GAYLORD H. CRAIN, OF MORRISVILLE, NEW YORK.

IMPROVEMENT IN TOILET-CASES.

Specification forming part of Letters Patent No. **190,287**, dated May 1, 1877; application filed February 24, 1877.

To all whom it may concern:

Be it known that I, GAYLORD H. CRAIN, of Morrisville, in the county of Madison and State of New York, have invented a new and valuable Improvement in Toilet-Cases; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a front elevation of my toilet-case, and Fig. 2 is a longitudinal vertical sectional view of the same. Figs. 3, 4, and 5 are transverse sectional views thereof.

The object of this invention is to provide an article of furniture which will contain or support the various articles needed for toilet use. This object is accomplished by the construction and arrangement hereinafter fully described.

In the accompanying drawings, A designates the rectangular frame of my devices. From the middle of the bottom piece of said frame a bar, A', extends obliquely forward and downward, to which is rigidly attached the middle of a horizontal bar or towel-rack, B. Said horizontal bar or rack is provided at its ends with expansions b b, which prevent the towels from being accidentally displaced.

C designates a shelf or mantel extending directly forward from the upper part of said frame and rigidly attached thereto. Above said shelf the back D of said casing is provided with a large opening, through which shows a mirror, E. Said mirror is held in place against the rear of said back piece D and frame A by means of a horizontal supporting-flange, d, a little below said opening, and grooved guide-pieces at the rear of its opposite sides. One of said guide-pieces (marked d') is shown in Fig. 2.

Below said mantel or shelf C a casing, F,

is secured to the front of frame A, and extends down nearly to the bottom of said frame. The said casing is divided into a series of compartments for the purpose of holding various toilet articles. The upper part of it contains a large compartment, G, for holding brushes and combs. Access is had to this compartment by means of a door, G', in front plate H of casing F. Below the middle of this comb and brush compartment is a smaller one, I, adapted to contain jewelry and other small articles. This is divided into two stories or portions by means of a horizontal partition, i, and provided with a door, I'. On one side of this jewelry-compartment I a pin-cushion, J, is set into a recess or compartment of said casing, and on the other side thereof a compartment, K, is closed by a door, L, on the inside of which are secured a match-holder, M, and a friction-cylinder, N, against which the matches are struck in lighting them.

O designates the cover of said casing, which sets over said front plate H and the compartments described above. The said cover is locked to casing F by any suitable lock, the case or plate of which (marked P) is shown in Fig. 1.

What I claim as new, and desire to secure by Letters Patent, is—

As a new article of manufacture, a toilet-case consisting of the frame A, towel-rack B, shelf C, mirror E, casing F, having compartments G and I, pin-cushion J, door L, match-holder M, friction-surface N, and cover O, substantially as described, and for the purpose set forth.

In testimony that I claim the above I have hereunto subscribed my name in the presence of two witnesses.

GAYLORD H. CRAIN.

Witnesses:

LUCIUS P. CLARK,
J. BENNETT BICKNELL.
